[57] CLAIM

The ornamental design for a radiotelpone face plate, as shown and described.

DESCRIPTION

FIG. 1 is a perspective view of the radiotelpone face plate showing our design illustrated in the environment of a radiotelpone;

FIG. 2 is a front view thereof;

FIG. 3 is a front view of an alternative embodiment of our design; and,

FIG. 4 is a front view of another alternative embodiment of our design.

The claimed radiotelpone face plate is used for the front face of a radiotelpone.

The rear, sides, and ends of the radiotelpone face plate form no part of the claimed design.

The broken lines shown herein are for illustrative purposes only and form no part of the claimed design.

1 Claim, 4 Drawing Sheets
